[57] CLAIM

The ornamental design for a clock, as shown and de-
scribed.

DESCRIPTION

FIG. 1 is a front elevational view of a clock showing my
new design;

FIG. 2 is a rear elevational view thereof;

FIG. 3 is a top plan view thereof;

FIG. 4 is a bottom plan view thereof; and

FIG. 5 is a right side elevational view thereof, the left
side being the same in appearance as the right side.

FIG. 1**FIG. 2****FIG. 3****FIG. 5****FIG. 4**
